Ramsay Hoguet

UNITED STATES PATENT OFFICE.

MARTIN A. MIKESCH, OF JERSEY CITY, NEW JERSEY, ASSIGNOR TO THE M. W. KELLOGG COMPANY, OF NEW YORK, N. Y., A CORPORATION OF DELAWARE.

MOLD FOR MULTIPLE RINGS.

Application filed March 10, 1927. Serial No. 174,201.

This invention relates to a multiple mold and more particularly to a mold for centrifugally casting a number of rings simultaneously.

In forming rings, such for example as pipe flanges, it is obviously desirable that a mold be used whereby a number of rings may be cast at once. In order to accomplish this result, a mold having a number of ring shaped chambers therein is required. The metal is ordinarily poured into the mold from one end and overflows from one chamber into another until all of the chambers are filled. Since the mold is being rotated during the pouring, the difficulty is encountered that due to the overflow from one chamber to the next, an annular web or shell is formed joining adjacent rings together. This shell or web must be broken away or removed in order to separate adjacent rings. Any means by which the size of the web may be reduced is therefore desirable since it will simplify the production of the rings.

By my invention I have provided a means of offsetting the openings between the various chambers so that the metal will flow from one compartment to another only during a portion of a revolution, thus reducing to a minimum the size of the web connecting the rings.

In carrying out my invention I provide a mold having therein a number of chambers which communicate with one another by means of annular openings, eccentrically arranged with respect to one another, and which in the preferred form have their centers removed an equal distance from the axis of the mold and arranged around the circumference of an imaginary circle at intervals of 90° so that a perpendicular dropped from the center of one opening to the axis of the mold is at right angles to perpendiculars similarly dropped from the centers of adjacent openings to the axis of the mold. I provide this symmetrical arrangement in order to maintain the balance of the mold, thereby keeping the centrifugal force of the rotating mold evenly distributed at all times.

My invention will best be understood if the following description is read in connection with the drawings in which like numerals refer to like parts and in which—

Figure 1 is a longitudinal section of the mold showing the eccentric manner in which

the communicating passageways between the chambers are arranged.

Figures 2, 3, 4, and 5 are transverse sections of the mold along the lines 2—2, 3—3, 4—4 and 5—5 respectively showing the center of each opening offset from the axis of the mold.

Figure 6 is a plan view of a completed casting made in accordance with my invention, showing the adjacent rings joined together by relatively narrow webs instead of by annular webs.

Figure 7 is an end view of the casting, the broken lines representing the webs joining successive pairs of rings.

The numeral 11 represents a mold having a refractory lining 12 which also serves to form the chambers 2, 3, 4, 5, 6, 7, 8, 9 and 10 in which the multiple rings are cast. Communicating with the end chambers 2 and 10 are the openings 13 in the ends of the mold, through which the spout 14 may be inserted in order to supply the metal to the mold.

Joining the chambers 2, 3, 4, 5, 6, 7, 8, 9 and 10 are the passageways 15, 16, 17, 18, 19, 20, 21 and 22 which are preferably of even size and have their centers disposed at intervals of 90° around the circumference of an imaginary circle concentric with the axis of the mold. Since the centers of the openings are spaced at intervals of 90° it will be readily apparent that each successive group of four openings will be similarly arranged so that the openings 15 and 19, 16 and 20, 17 and 21 and 18 and 22 will be concentrically arranged. The four positions of the openings are shown respectively in Figures 2, 3, 4, and 5 while they are numbered to represent openings 15, 16, 17 and 18 as pointed out above. They also serve to represent each successive group of four openings. It will be obvious that the centers of the openings may be angularly spaced apart by any desired amount and the number of openings occurring in 360° varied accordingly. Any suitable number of openings may be employed but they should be evenly spaced from one another about the axis of the mold so that the balance of the mold will be maintained.

In Figure 6 the finished casting is shown comprising rings 32, 33, 34, 35, 36, 37, 38, 39 and 40, adjacent rings being joined together by the webs 41. In Figure 7 the size of the webbing is further illustrated in end view,

the webs joining the first five rings being shown in broken line, constituting arcs disposed about the central opening in the casting, shown in solid line. It is apparent from 5 the illustration that the web formed between adjacent rings cast in my improved mold disclosed herein is relatively small and easy to break off thereby facilitating the separation of the rings.

10 While I have described above one modification of my invention, it is to be understood that I do not limit myself to the specific embodiment set forth herein but only by the following claims:

15 1. A mold comprising a number of chambers and a number of passageways joining said chambers, each of said passageways being eccentrically disposed with respect to the axis of the mold and with respect to each 20 other.

2. A mold comprising a number of chambers and a number of passageways joining said chambers, said passageways being eccentrically disposed with respect to the axis 25 of the mold and with respect to each other, and also collectively defining a longitudinal passage through the mold including the axis thereof.

3. A mold for casting multiple rings centrifugally, comprising a substantially cylindrical member having interiorly a number of chambers, partitions between said chambers, said partitions having openings therethrough of equal diameter and including the axis of 35 the mold, the center of each of said openings being removed an equal distance from the axis of the mold.

4. A mold for casting multiple rings centrifugally, comprising a substantially cylindrical, rotatable hollow member having an 40 opening for receiving molten metal, and having interiorly a number of chambers sepa-

rated by partition walls, said partition walls having circular apertures therethrough permitting the metal to flow from one chamber 45 to the next, each of said apertures including the axis of the cylinder and having its center positioned an equal distance from said axis, and being angularly disposed with respect to one another about the axis of the mold. 50

5. A mold for simultaneously casting a number of rings centrifugally comprising a cylindrical member, having interiorly a core comprising a number of chambers, each of said chambers communicating with adjacent 55 chambers by means of passageways, said passageways being eccentrically positioned with respect to, but including, the axis of said core, and adjoining passageways being eccentrically positioned with respect to each other. 60

6. A mold for simultaneously casting a number of rings centrifugally, comprising a cylindrical mold having interiorly a core, said core being formed to provide a number of annular chambers partially separated by 65 partition walls but communicating with adjacent chambers by means of circular openings extending through said partition walls, the centers of each of said openings being disposed at intervals of 90° around the circumference of an imaginary circle having the axis of the mold for its center. 70

7. A mold comprising a number of chambers communicating with one another by means of eccentrically arranged circular 75 openings, said openings being of equal radius and positioned successively at equal angular distances around the axis of said mold, and also collectively defining a longitudinal passage including the axis of the mold. 80

In testimony whereof, I have signed my name to this specification this 2nd day of March, 1927.

M. A. MIKESH.
